UNITED STATES PATENT OFFICE

EARL V. STEINER, OF MARSHALLVILLE, OHIO

SIGNALING SYSTEM FOR RAILWAY CROSSINGS

Application filed September 27, 1929. Serial No. 395,658.

This invention relates to railway signaling systems, and particularly to a system for use in operating signals or guards at railway crossings.

- 5 With the systems now in general use, an electric circuit for a signal is established at a predetermined location with respect to the crossing and trains approaching the crossing reach the same at different intervals of 10 time, depending upon the speed of the train. When a delay occurs between the time the signal is displayed and the appearance of the train, persons constituting the traveling public become careless and attempt to pass the 15 track before the train can reach it and they frequently succeed in this effort, especially when the train is traveling slowly, but they are sometimes caught on the track when the train is traveling fast and disasters result. 20 The present systems tempt the hazardous use of the road and often decoy the travelers.

It is an object of this invention to produce a signaling system in which the train whether traveling fast or slowly will arrive 25 at the crossing a predetermined time after the signal is in operation, the object being attained primarily through the employment of means by which the time of displaying the signal is retarded, after the current is 30 established through the system by a slow moving train, and made to operate normally when the current is established by a fast train, although provision is made for establishing the circuit to display the signal at 35 other periods between that of the slow moving train and the fast moving train. In other words, the circuit to the signal is established by the train and the signal is made operative according to the speed of the train, 40 so that within approximately fifteen seconds after the signal is displayed, the train will arrive at the crossing, although it is possible to so regulate the system as to vary this time period of warning to suit particular requirements.

It is a further object of this invention to provide means whereby a train after it has passed a crossing will operate the signaling system so that it will not be energized for 45 establishing a circuit for the signal, as, of

course, it would not be desirable to create a signal after the train had passed the location of danger.

It is a still further object of this invention to provide a signaling system which will be 55 positive in its operation, and easily controlled for increasing or diminishing the time between the establishment of the circuit and the display of the signal, the same comprising comparatively few inexpensive parts 60 to be efficient and satisfactory in use.

With the foregoing and other objects in view, the invention consists in the details of construction, and in the arrangement and combination of parts to be hereinafter more 65 fully set forth and claimed.

In describing the invention in detail, reference will be had to the accompanying drawings forming part of this application, wherein like characters denote corresponding parts in the several views, and in which—

Figure 1 illustrates a diagrammatic view of a system embodying the invention; Figure 2 illustrates a detail view in section of a means for establishing or retarding 75 the circuit to the signal;

Figure 3 illustrates a modification of the mechanical means for establishing the circuit to the signal;

Figure 4 illustrates a view in elevation of 80 mechanism for establishing a circuit and controlling the same, the said mechanism being mainly electrically controlled and operated;

Figure 5 illustrates a plan view of a lever associated with the mechanism shown in Figure 4; and

Figure 6 illustrates a detail view of a receptacle and its weights.

In these drawings, 10 and 11 denote the rails of a railway track, and the said rail 11 90 has a conductor 12 leading to a battery 13. The rail 10 is preferably arranged in sections insulated from one another, as will presently appear. The rail section 14 has a conductor 15 leading to a switch 16 which is held normally in contact with a terminal 17 through the employment of usual devices, such as a spring 18 or the like. The switch 16 is operated against the action of the spring 95 by an electromagnet 19, under certain con- 100

ditions, and its winding has a conductor 20 connected to an insulated section 21 of the rail that has been generally identified by the numeral 10, and the winding of the said electromagnet also has a conductor 22 leading to the battery 13.

The switch terminal 17 has a conductor 23 connected to the winding of an electromagnet 24 and the said winding has a conductor 25 leading to the battery 13.

10 A lever or oscillative arm 26 is pivoted on a post 27 and the said lever carries a metal plate 28 in operative relation to the electromagnet 24 so that when the said magnet is 15 energized it will pull that end of the lever beyond the post 27 downwardly, for a purpose to be presently explained.

At the outer end of the lever or, at some 20 location with relation to which the lever may operate, a receptacle 29 is located and this receptacle is intended to contain a fluid which is a good conductor of electricity. It has been found in practice that quicksilver is a 25 satisfactory medium for use in this connection. The lever supports a member 30 whose function is to receive the fluid when the said members enters the receptacle 29 and it is effective to gradually and uniformly release the fluid as it is elevated with relation to the 30 fluid. In the present embodiment of the invention, this is accomplished through the instrumentalities by which the member is suspended from the lever and holes which are formed in the member 30. As here shown, 35 the member has an arm 31 whose upper end is pivotally connected at 32 to the lever. The side wall of the member has an aperture 33 in its side and an aperture 34, relatively smaller than the aperture 33, in its bottom. 40 The graduated sizes of these apertures may be changed to increase or diminish the rapidity of flow of the fluid into or out of the member, according to the time interval between the establishment of the circuit for a 45 signal and the time the signal is to be displayed, for, it is through the employment of the fluid, in the present embodiment of the invention, which coacts with terminals in the member 30, that the interval between 50 the establishment of a circuit to a signal and the time of the display of the signal is regulated, as will presently appear.

As here shown, a terminal 35 extends downwardly in the member 30 to a lower level 55 than a terminal 36 therein. The terminal 35 has a conductor 37 leading to the signal 38. The conductor 36 has a conductor 39 in circuit with the windings of an electromagnet 40, battery 13 and a switch terminal 41. A 60 conductor 42 in circuit with the signal leads to a switch 43 which coacts with the switch terminal 41 to establish a circuit from the battery to the signal. The signal circuit is interrupted or broken when the electromagnet 40 is energized as it attracts the switch 43

and breaks the circuit. The purpose of this operation will be presently explained. The receptacle 29 contains an electrode 44 which is submerged in the fluid therein and this electrode is connected by a conductor 45 with the battery.

In the operation of the signal, when the fluid in the receptacle 29 reaches the level of the terminal or electrode 35, a circuit is established through the fluid to the electrode 44 and to the battery and from the battery through the switch terminal 41, the switch 43, the conductor 42 to the signal. If, however, the fluid in the receptacle 29 is high enough to immerse the lower end or any part of the terminal or electrode 36, the electromagnet attracts the switch 43 and breaks the circuit from the battery to the signal and, so long as sufficient fluid remains in the member 30 and engages the terminal or electrode 36, the circuit through the signal will remain broken and the signal will not be operated, but, when the fluid is out of contact with that terminal, the electromagnet 40 is demagnetized, the switch resumes its engagement with its terminal and a circuit is established through the signal and maintained until the fluid in the member 30 has passed below the end of the electrode or terminal 35.

The member 30 is articulated with respect to the lever and at times assumes a position diagonal with respect to the level of the fluid in the receptacle, but, when the end of the lever to which the member 30 is connected is elevated, the bottom of the member 30 is approximately parallel with the level of the top of the fluid in the receptacle.

A bracket 46 is applied to the lever and it has a threaded portion 47 which is parallel with the lever. A weight 48 is threaded on this part of the bracket in order that the weight may be adjusted relative to the pivot of the lever and this acts as a counterbalance weight to allow for the displacement of the material comprised in the construction of the member 30.

From what has been illustrated and so far described, it will be apparent that a train traveling on the track from the left hand to the right hand side of the drawing will cause a circuit to be established through the electromagnet 24 when and while the forward truck of the train passes over section 14 of the track and during such time the magnet will exert a pull on the lever 26 and thus the member 30 will be allowed to gravitate into the fluid of the receptacle 29. After the front first truck of the train, engine or motor has passed onto the section 21 of the rail, current is established through the electromagnet 19 which serves to move the switch 16 out of engagement with the terminal 17 and this demagnetizes the electromagnet 24 and the lever is therefore released from the influence of the electromagnet. The lever has a shiftable weight 49 on

the side of the pivot of the lever opposite that carrying the member 30 and this weight is sufficient to normally overcome the weight of the member 30, its contents and parts associated with it. Hence, the weight gradually lifts the member or moves it with respect to the fluid in the receptacle 29 and causes the aperture 33 of the member 30 to be lifted clear of the fluid in the receptacle and, as the said receptacle is raised, the fluid flows therefrom through the orifice 34. The flow is gradual and is timed, as before stated, for the purpose of regulating the time during which the signal will be displayed. The position and size 15 of the weight 49 may determine the rapidity of the rise of the receptacle 29 and the timing of the signal.

The system also includes means for preventing the energization of the system when 20 the train is traveling in a reverse direction to that just described. The means for accomplishing this result includes a switch terminal 50 having a conductor 51 which is in circuit with the electromagnet 19 and with a conductor 25 20 leading to the rail section 21. A train or rolling stock of any type traveling on the track and reaching the section 21 will establish a circuit through the electromagnet 19, and the switch 16 will be drawn thereby into 30 contact with the terminal 50, and, when any truck of the rolling stock passes into engagement with and over the insulated section 14, circuit will be established through the conductor 15, the switch 16 and switch terminal 35 50, conductor 51 and through the electromagnet 19 to hold the switch out of engagement with the terminal 17 so that the signal system is not energized.

The member 30 is provided with counter- 40 balance weights which extend downwardly at the sides of the receptacle 29 below the center of gravity of the receptacle of the member 30, these weights being identified by the numeral 52.

45 While reference has been made specifically to a battery in association with the system, it is to be understood that this contemplates the provision of any source of electric energy, whether it be a battery, generator or a substitute therefor.

In the modified construction illustrated in Figures 3, 4 and 5, the operation heretofore described is effected, but the mechanism for effecting the same result is similar to the member 30, cup-shaped, as shown by Figure 2, and it has an opening in its bottom and is associated with means for partially submerging it in the fluid as illustrated.

The lever 26 is in coactive relation to a post 53 that has horizontally disposed arms 54 and 55 in spaced relation to each other and these arms act as stops for limiting the movement of the lever, it being shown that the lever may move upwardly and downwardly in the 65 space between the two arms. Figures 3, 4 and

5 show a form of the invention wherein a lever 56, corresponding to the lever 26 heretofore described, is to be pivotally mounted on a post 57 and in coactive relation to a post 58 which may have adjustable arms 59 and 60 in spaced relation to each other to limit the movement of the lever 56. The arms are adjustable in holes, such as 61, in the post 58, or other means may be afforded for adjustably limiting the swing of the lever 56. This lever 70 also has other features in common with that illustrated in Figure 1, which need not, it is thought, be more specifically described, such as the weights and their association with the lever.

75 One end of the lever is provided with an extension 62 having rearwardly extending spaced sides 63 and 64 which lie parallel with the lever 56 and the extensions 63 and 64 are oscillative on a pivot 65 extending through the lever 56. The under side of the lever 56 at any suitable location may be provided with an armature 66 to be attracted by the core of an electromagnet 67, or other means for moving the lever when current is supplied for the purpose may be employed in this connection.

80 A switch terminal 68 is attached to the under side of the extension 62 of the lever, whereas the lever itself has a switch 69 which makes and breaks a circuit, as will presently appear.

85 A cup-like fluid receiver 70 has an aperture 71 in its bottom and the said fluid receiver has a flared extension 72 communicating with said opening in order that when the fluid receiver is gravitated in the fluid, the said fluid will 90 be directed toward the opening to more effectively insure the entrance of the fluid to the said receiver. Under certain conditions, the opening 71 is controlled by a valve 73 having a valve stem 74 extending upwardly and connected to a link 75 which depends from a lever 76 on one side of its pivot 76^a, which pivot is supported by a post 77 carried by the extension 62. A link 78 is connected to the lever 76 on the other side of the pivot of the lever 100 and this link is anchored in suitable manner to the lever 56. The fluid receiver is provided with a drain opening 79 and this may be formed in the receiver itself or in the valve and it has the same function as the orifice 34 105

110 in the member 30 to gradually release the fluid which it contains. An electrode 80 extends into the fluid receiver 70 and it has a conductor 81 leading to the switch terminal 68. The fluid receiver acts in conjunction with a fluid 115 tank or holder 82 and this holder has an electrode or conductor 83 which is similar to the electrode 44 of Figure 1 and is intended to function in the same way in connection with a circuit similar to that illustrated in Figure 120 1. An electrode 84 is also associated with the fluid receiver 70, but it does not extend as far down into the fluid receiver as the electrode 80. It has a conductor 85 which is intended 125 to be coupled up with a circuit similar to that

to which the conductor 39 is connected in Figure 1 and, so long as fluid in the receiver 70 is in engagement with the electrode 84, a circuit to a lamp or signal will be interrupted, 5 but the said circuit will be closed when current is no longer available through the conductor 85 and then current could be established to the signal through the electrode 80, conductor 81, switch terminal 68, switch 69 and a conductor connected to it.

10 When the electromagnet 67 draws the lever 56 downwardly and the fluid receiver 70 encounters the fluid in the holder 82, the downward movement of the extension lever 15 62 will be retarded, as compared with the movement of the lever 56 and, as the lever 56 continues downwardly at a greater acceleration than that of the extension 62, a pull will be exerted on the link 78 and this 20 will tilt the lever 76 to raise the link 75 and the valve and valve stem to which it is connected so that the opening 73 in the fluid receiver is unguarded and the fluid may flow into the receiver. The movement just described 25 also breaks the connection through the switch 69 and this circuit is not re-established until the magnet 67 is demagnetized and the lever 56 is moved in the opposite direction under the influence of a weight 86 30 which functions in a manner similar to the weight 49 of that form of the invention shown in Fig. 1.

The extension lever 62 is supplied with a weight 87 which is suspended from the said 35 lever by an arm 88 of a length which permits the weight to move below the center of gravity of the fluid receiver 70.

In the use of the mechanism just described, an electromagnet 89, a switch 90 operated 40 thereby and switch terminals 91 and 92 with which the switch contacts are provided with conductors, as the circuit is diagrammatically shown in Fig. 1, connecting a battery, rails and the electromagnet 67, which corresponds 45 to the electromagnet 24 in the diagram of Fig. 1. The electromagnet 93 is intended to be used in the same circuit as that in which the electromagnet 40 is included in Fig. 1 so that the main difference 50 in the modified construction relates to the manner of partially submerging the fluid receiver 70, in releasing the fluid from the receiver, and in the structure and operation of the lever and its extension.

55 Referring to the description of the circuits in Fig. 1 and the manner of delaying the signal for fast or slow moving trains, the modified construction has the same provision, in that, as heretofore stated, a fast 60 moving train will cause the energization of the magnet 67 for a shorter time than will be the case where a slow moving train is traveling over the track. The fast moving train will therefore cause the fluid receiver 65 70 to be held in the fluid a comparatively

short time before it is released by the magnet and the weight begins to exercise its function in raising the said receiver from the container. On the other hand, a slow moving train will maintain the current through the electromagnet 67 a greater length of time, holding the fluid receiver 70 depressed in the fluid so that a greater amount of fluid enters the said receiver, and after it reaches a height therein so that it contacts the electrode 84, the switch through the signaling system will be open and the signal will not be energized until the fluid flows out of the receiver to clear the end of the electrode 84.

70 From the foregoing, it will be noted that the purpose of the invention is to provide a signaling system which will eliminate the unnecessary time period of the signal when a slowly moving train approaches a crossing, for instance, fixing a definite period of time before a train arrives at the crossing, and the time period varies inversely with the speed of the train.

75 The single coil 19 is operative when a train is approaching the crossing, it also times the action of coil 24 of armature 66, and this coil with its wiring does double duty, as it eliminates action when a train is leaving a crossing, and times the action of the signal for an approaching train, being operative 80 in case of a single track railroad.

85 I claim:

1. In a signaling system for railway crossings, a signal for the crossing in an electric circuit including a switch, a fluid time-controlled contact maker and breaker for establishing a circuit through the signal and the switch, the action of said means being proportional to the speed of rolling stock on the railway approaching the crossing.

100 2. In a signaling system for railway crossings, a signal for the crossing in an electric circuit, means for controlling the circuit through the signal, the said means including a fluid level circuit maker and breaker whose operation is regulated proportional to the speed of rolling stock on the railway approaching the crossing.

105 3. In a signaling system for railway crossings, a signal for the crossing in an electric circuit, a container having fluid therein for conducting electric current, a member mounted for movement in the fluid and adapted to receive the fluid proportional to the time in which it is in the fluid and discharge said fluid gradually, conductors of electricity in said member terminating at different levels therein, one of said conductors being included in the circuit of the signal, electrically controlled means for making and breaking the said signal circuit, including a source of electricity, a circuit for the said means including the other of said conductors in the member, the last mentioned conductor being in circuit while fluid in the member is in contact 110 115 120 125 130

with it, and the circuit in which it is included being demagnetized when fluid in the member recedes beyond the said conductor.

4. In a signaling system for railway crossings, a signal for the crossing in an electric circuit, a container having fluid therein for conducting electric current, a member mounted for movement in the fluid and adapted to receive the fluid proportional to the time in which it is in the fluid and discharge said fluid gradually, means controlled by a circuit including rolling stock on the railway for moving the said member for graduated submergence in the fluid, means for lifting said member partially or wholly out of the fluid, conductors of electricity in said member terminating at different levels therein, one of said conductors being included in the circuit of the signal, electrically controlled means for making and breaking the said signal circuit, including a source of electricity, a circuit for the said means including the other of said conductors in the member, said last mentioned conductor being in circuit while fluid in the member is in contact with it, and the circuit in which it is included being demagnetized when fluid in the member recedes beyond the said conductor.

5. In a signaling system for railway crossings, a signal for the crossing in an electric circuit, means for establishing a circuit through the signal, and a fluid circuit maker and breaker of such construction as to constitute means for controlling the time of establishing a circuit complementary to the speed of rolling stock on the railway approaching the crossing.

6. In a signaling system for railway crossings, a signal for the crossing in an electric circuit, means for establishing a circuit through the signal, and means for timing the establishment of the circuit with relation to the speed of travel of the rolling stock approaching the crossing, effected by a fluid contact circuit maker and breaker.

EARL V. STEINER.
